Patented Oct. 24, 1922.

Inventor
Julia A. Brady
by W. M. Monroe
Attorney

UNITED STATES PATENT OFFICE.

HUBER R. BRADY, OF PITTSBURGH, PENNSYLVANIA.

COLLAPSIBLE TABLE.

Application filed December 27, 1920. Serial No. 433,221.

To all whom it may concern:

Be it known that I, HUBER R. BRADY, a citizen of the United States and resident of Pittsburgh, in the county of Allegheny and State of Pennsylvania, have invented 5 certain new and useful Improvements in Collapsible Tables, of which I hereby declare the following to be a full, clear, and exact description, such as will enable others skilled in the art to which it appertains to 10 make and use the same.

The objects of the invention are to provide an improved and simple form of construction for a folding table, in which the 15 frame, legs, and cover can be expanded to form a rigid structure, suitable for use as a card or picnic table, or at will can be collapsed and made to enter a small and narrow bag, easily transported and capable 20 of being stored in a small space.

The invention comprises a rectangular frame, the members or rails of which are pivoted together at different levels by vertical pins or bolts, and legs which are pivoted one to each rail at the same end thereof, and fold parallel with their respective rails 25 and closely against the same.

Bracing means are also employed to secure the legs in a vertical position, and recesses are formed in the legs or provided 30 for between the legs and side rails, in which the bracing means are concealed when the parts are folded together.

The cover or top of the table is also formed 35 of folding slats which may be connected together by means of flexible material, and the corners are detachably secured to the corners of the frames, the slats may fit into recesses in the side rails.

40 The invention is hereinafter further described, shown in the accompanying drawings, and specifically pointed out in the claims.

In the accompanying drawings, Fig. 1 is 45 a plan of the device; Fig. 2 is a side elevation thereof; Fig. 3 is a perspective of the unfolded table; Fig. 4 is an enlarged elevation of one corner; Fig. 5 is a plan of the folded table; Fig. 5^a shows the same partly 50 folded; Fig. 6 is an enlarged view of one edge of Fig. 5; Fig. 7 is an end view of Fig. 6; Fig. 8 is a perspective of the joint on one

of the leg braces; Fig. 9 is a side elevation of a modified form of top.

In these views, A, A, are four horizontal 55 rails, pivoted together at B, B, over which a folding top composed of slats, C, C, flexibly connected together by means of fabric strips, D, D, is stretched. This top is secured at the corners by means of buttons, 60 E, upon the rails, and eyelets, F, F, or analogous means, in the preferred form, shown in Figs. 1 and 2.

In Fig. 9, the side rails are formed with a sunken shoulder, G, and the slats, G', 65 which compose the top, are merely set therein. Dowel pins G² secure the slats in place. H, H, are the legs, which are pivoted at I, to the ends of alternate rails, one leg only 70 to each rail. The pivots are horizontal so that the legs, H, will fold closely against the rails, A, A, and jointed brace bars, J, J, are pivoted to the legs and the adjacent rails, and are provided with keepers, K, K, 75 which are provided with shoulders, K', K', which overlap the jointed parts and prevent them from passing the rigid position when they are in alignment with each other. Recesses, L, L, are formed in the legs, in which the folded braces are entirely enclosed, when 80 the legs are folded against the rails.

When all the legs are folded in place against their respective rails, one pivot pin, as P, is removed from the rails and they can then be folded together as shown in Figs. 85 5, 5^a, and 6.

Having described the invention, what I claim as new, and desire to secure by Letters Patent, is:

1. In a folding table, upper and lower 90 side rails, pivoted together at their extremities and foldable together, side by side, one of said pivots being removable to permit such operation, a leg pivoted to each rail at one end thereof, said legs being positioned at the corresponding ends of alternate rails and folding braces for said legs, said braces pivotally attached to said legs and to said rails, said legs provided with recesses in which said braces are enclosed when said 100 legs are folded against said rails.

2. In a folding table, upper and lower side rails, pivoted together at their extremities and foldable together, side by side, one

of said pivots being removable to permit such operation, a leg pivoted to each rail at one end thereof, said legs being positioned at the corresponding ends of alternate rails; and folding braces for said legs, said braces pivotally attached to said legs and to said rails, said legs provided with recesses in which said braces are enclosed when said legs are folded against said rails, and keepers upon the folding joints of said braces, said

keepers provided with shoulders limiting the movements of the folding parts of said braces.

15

In testimony whereof, I hereunto set my hand this 15th day of September, 1920.

HUBER R. BRADY.

In presence of—

W.M. M. MONROE,
CHAS. F. SYPE.
